UNITED STATES PATENT OFFICE.

EDMUND F. HARTSHORN, OF NEWARK, NEW JERSEY, ASSIGNOR TO THE STEWART HARTSHORN COMPANY, OF NEW JERSEY.

DESIGN FOR A BRACKET FOR ROLLERS.

SPECIFICATION forming part of Design No. 32,493, dated April 10, 1900.

Application filed November 11, 1899. Serial No. 736,703. Term of patent 14 years.

To all whom it may concern:

Be it known that I, EDMUND F. HARTSHORN, a citizen of the United States of America, and a resident of Newark, county of Essex, State 5 of New Jersey, have invented a certain new and original Design for a Bracket for Rollers, of which the following is a specification.

In the accompanying drawings, forming part of this specification, Figures 1 and 2 are 10 views of the bracket formed according to my invention.

As shown in the drawings, the design of the bracket consists of the parallel flanges *a* and *b*, connected by the central curved part *c* at 15 right angles to the flanges *a* and *b* and diagonal to their horizontal planes.

As shown, the flange *b* is narrower and longer in a horizontal plane than the flange *a*, and in the outer end of this flange *b* is the hole or opening *d*. 20

What I claim is—

The design for a bracket for rollers as herein shown and described.

Signed by me at Newark, New Jersey, this 22d day of April, A. D. 1899.

EDMUND F. HARTSHORN.
